(57) **CLAIM**

The ornamental design for a car body, as shown and described.

DESCRIPTION

FIG. 1 is a front elevational view of a car body showing our new design;

FIG. 2 is a rear elevational view thereof;

FIG. 3 is a left side elevational view thereof;

FIG. 4 is a front and right side perspective view thereof;

FIG. 5 is a rear and right side perspective view thereof;

FIG. 6 is a right side elevational view thereof; and,

FIG. 7 is a top plan view thereof;

FIG. 8 is a front elevational view of a car body showing a second embodiment of our new design;

FIG. 9 is a rear elevational view of FIG. 8;

FIG. 10 is a left side elevational view of FIG. 8;

FIG. 11 is a front and right side perspective view of FIG. 8;

FIG. 12 is a rear and right side perspective view of FIG. 8;

FIG. 13 is a right side elevational view of FIG. 8; and,

FIG. 14 is a top plan view of FIG. 8.

The broken lines shown in the drawings are for illustrative purposes only and form no part of the claimed design.
